UNITED STATES PATENT OFFICE.

DANIEL KOPS, OF NEW YORK, N. Y., ASSIGNOR TO KOPS BROTHERS, INC., OF NEW YORK, N. Y., A CORPORATION OF NEW YORK.

APPAREL GARMENT.

Application filed April 29, 1922. Serial No. 557,342.

To all whom it may concern:

Be it known that I, DANIEL KOPS, a citizen of the United States, residing in the borough of Manhattan, city, county, and 5 State of New York, have invented an Improvement in Apparel Garments, of which the following is a specification.

The prevailing tendency in the use of corsets is to produce the appearance of a natural or uncorseted figure so far as the same 10 is possible, and the corset made in accordance with my present invention is designed to produce this result and includes a construction which is an improvement upon and 15 a modification of the form of garment shown and described in Letters Patent No. 1,432,470, granted to me October 17, 1922.

The object of the invention in the present case, as well as in that of the application to 20 which I have referred, is a garment in the use of which a natural or uncorseted figure effect may be obtained and at the same time sufficient support be provided for the underlying portions of the body of the wearer, 25 particularly at the groin section thereof. The corset made in accordance with this invention is preferably a closed back garment, although, as will be understood, the invention is not limited to use in a closed back 30 corset. The corset is constructed with the front members each comprising a front steel section, a section of yielding fabric or other similar material between each front steel section and the adjacent portion of the body 35 of the garment, which yielding section preferably extends from the upper to the lower edge of the garment, together with adjusting tension and supporting devices extending from approximately the waistline to the 40 groin section of the wearer and so embodied in the garment as to be readily adjustable to position in a manner similar to that described in my application aforesaid. In the garment made in accordance with this 45 invention, however, the lower front portions of these adjusting tension and supporting devices are connected to the lower extremities of the front steels, and there are overlying extensions depending from the front 50 steel sections which assume a substantially straight line position, while the lower edges of the adjusting tension and supporting devices are made to conform to the groin section of the wearer, and in being adjusted to 55 position exert a tension against the lower ex-

tremities of the front steel to form a continuous pressure against the groin section of the wearer to provide a more adequate support therefor than is obtained by the use of the garment as shown and described in my 60 aforesaid application.

In the drawing:

Fig. 1 is a perspective view illustrating a corset made in accordance with this invention. 65

Fig. 2 is an elevation on an enlarged scale showing the front inner portion of the garment.

Fig. 3 is a longitudinal section on a still larger scale illustrating the manner in 70 which the lower portion of the front steel section overlies the lower extremities of the front steel, and

Fig. 4 is a cross section illustrating a modified construction of separating the lower end of the adjusting tension and supporting devices. 75

Referring to the drawing, and particularly to Figs. 1 to 3 inclusive, the corset garment made in accordance with this invention, together with the usual body member which in this garment is closed at the back, includes front steel sections indicated at 10 and 11. Each front steel section is fitted with a front steel in one of which there are the usual stud members 12 and connected to the other usual socket members 13 forming the clasps by which the garment at the front edges thereof is connected on the body. The front steel section 10 includes an extension 14 and the front steel section 11 a corresponding extension 15. These extensions of the front steel sections overlie the lower extremities of the corset steels and are entirely free therefrom from predetermined distances above the lower edges thereof which, for example, may be indicated by the lines 16 and 17, whereas the lower ends of the corset steels are indicated respectively at 18 and 19. In a suitable position in 90 these extensions 14 and 15 of the front steel sections I may employ a clasp 20 by which the edges are connected to one another; and also in these extensions of the front steel sections I prefer to employ eyelets 21 through which a lace 22 is threaded for drawing together and securing in position the lower extremities of these overlying extensions of the front steel sections. 95

Inasmuch as the front sections of the gar- 110

ment are similarly constructed but one of these will be specifically described. These front sections include yielding members 23 and 24 made of elastic fabric or other similar material and of predetermined width extending from the upper to the lower edges of the garment and connecting the front steel sections with the body portions thereof. In each front portion of the garment I employ an adjusting tension and supporting device. Each of these comprises an adjusting strap 25 which is connected to the front steel section and at the lower end thereof to the front steel so that a portion 10 of the front steel section overlies a portion, that is the lower portion of the adjusting strap 25. This adjusting strap 25 extends from the lower end of the front steel to approximately the waistline of the garment and is secured to the front steel section and the cover of the front steel in any suitable manner. The opposite edge of the adjusting strap 25 is provided with eyelets 26. Associated with the adjusting strap 25 is an anchor strap 27. This is provided with eyelets 26 corresponding in number with the eyelets 28 and the adjusting strap and a lace 29 threaded through the eyelets 26 and 28 and also through eyelets 30 in the adjacent 20 portion of the body of the garment so as to extend to the exterior thereof where, after adjusting the straps to position by drawing on the lace, the lace may be tied in a bow or knot as indicated at 31 to secure the parts of the garment in position. As indicated in the drawing, each adjusting tension and supporting device underlies the yielding fabric section at the front of the garment, and as clearly indicated in Fig. 2 the lower end of 30 the adjusting strap 25 may be provided with a reinforcing strip 32 which in this instance is secured thereto by suitable rows of stitching indicated at 33.

In the form of the invention indicated in 40 Figs. 1, 2 and 3 of the drawing, the adjusting strap 25 is made of inelastic material including the reinforcing strip 32 secured to the lower end thereof. In some instances, however, particularly where a more yielding 45 effect is desired the reinforcing strip 32 may be dispensed with and a tension strip indicated at 34 be used in its stead. In this structure, as is indicated in Fig. 4, the extremities of the yielding strip 34 are connected respectively to the extremity of the corset steel and the lacing edge of the adjusting strap, but this strip is not otherwise attached thereto. Furthermore, the length of 50 this yielding reinforcing strip is somewhat less than the width of the adjusting strap at the lower end thereof so that in adjusting the parts to place the tension applied causes the separate reinforcing strip to yield at least to the extent of the width of the adjusting strap in order to produce a greater 55

yielding effect than when the entire adjusting strap is made inelastic.

In the use of the garment, as hereinbefore described, as will now be apparent, the lower edges of the adjusting tension and supporting devices are permitted to conform to the groin sections of the wearer without in any way affecting or influencing the outer contour of the garment and will manifestly lend a greater support to the groin section 75 of the wearer than is possible with the garment constructed in accordance with the disclosure made in my aforesaid application.

I claim as my invention:

1. In an apparel corset and in each front portion thereof, a front steel section, an elastic section between the front steel section and the adjacent portion of the body of the garment extending from the upper to the lower parts thereof, an adjustable inelastic supporting device on the inner side of the garment extending substantially from the waistline to the groin section, and a depending front skirt extension overlying the lower end portions of the front steel sections. 80

2. In an apparel corset and in each front portion thereof, a front steel section, an elastic fabric section between the front steel section and the adjacent portion of the body of the garment extending from the upper to the lower edges thereof, an adjustable inelastic supporting device coextensive circumferentially with the elastic fabric section and extending substantially from the waistline to the groin section on the inner side of the garment, and a front skirt extension overlying the lower end of the front steel section. 95

3. In an apparel corset and in each front portion thereof, a front steel section, an elastic fabric section between the front steel section and the adjacent portion of the body of the garment extending from the upper to the lower edges thereof, an inelastic supporting device underlying the elastic fabric section and extending from approximately the waistline to the groin section of the garment, means for adjusting the said supporting device to position exteriorly of the garment, and a front skirt extension overlying the lower end of the front steel section. 100

4. In an apparel corset and in each front portion thereof, a front steel section, an elastic fabric section extending between the front steel section and the adjacent portion of the body of the garment and also from the top to the bottom edges thereof, an inelastic strap secured along one edge to the front steel section extending upwardly from the lower end thereof, an inelastic strap secured along one edge to the forward section of the body of the garment, the said straps extending from approximately the waistline to the groin section on the inner side of the garment, means for adjusting the 115

relative positions of the said straps to secure the garment in position on the body of the wearer, and a front skirt extension overlying the lower ends of the front steel section.

5 5. In an apparel corset and in each front portion thereof, a front steel section, an elastic fabric section extending between the front steel section and the adjacent portion of the body of the garment and also from 10 the top to the bottom edges thereof, an inelastic strap secured along one edge to the front steel section extending upwardly from the lower end thereof, an inelastic strap secured along one edge to the forward sec-

tion of the body of the garment along a 15 portion of the adjacent edge of the elastic section, the said straps extending from approximately the waistline to the groin section of the garment, a lace threaded through the adjacent edges of the said straps and 20 passing to the outer side of the garment for adjusting the said straps relatively to position in adjusting the garment on the body of the wearer, and a front skirt extension overlying the lower end of the front 25 steel section.

Signed by me this 24th day of April, 1922.

DANIEL KOPS.
